Specification of Letters Patent. Patented Mar. 7, 1916.

Application filed May 21, 1913. Serial No. 768,912.

To all whom it may concern:

Be it known that I, GEORGE L. MASON, a citizen of the United States of America, residing at Warehouse Point, in the county of 5 Hartford and State of Connecticut, have invented new and useful Improvements in Trucks, of which the following is a specification.

This invention relates to an elevating truck. As pointed out in my co-pending application, Serial No. 768,912, filed May 21, 1913, trucks of this character heretofore constructed have all been objectionable because unsound on mechanical theory. These 10 trucks, in general, comprise a base portion and a lifting platform, together with a steering handle and means whereby the platform is elevated when the steering handle is depressed; but, in so far as I have been aware 15 and before my invention, the lifting devices for the platform have been so arranged that they either take their greatest movement to correspond with the beginning of the downward movement of the steering handle, or 20 the movement of the platform and handle corresponds throughout, the upward movement of the platform either falling off or remaining the same as the handle continues to be depressed. My invention, on the other 25 hand, in addition to numerous other features, some of which I shall point out particularly hereinafter, involves an arrangement whereby the lift of the platform takes place very slowly at the time when the 30 handle is beginning to be depressed, the rate of upward movement of the platform increasing thereafter, thus giving an "easy start" as opposed to the "stiff start" of devices heretofore constructed for this purpose. This is an important advantage, for 35 the reason that the loads to be raised by the platform of these trucks frequently are considerably over a ton in weight, and therefore mechanisms which enable the operator 40 to get a "purchase" on the load at the beginning of its upward movement are important and highly desirable.

Another all important advantage inherent in my new truck is involved in the arrangement whereby I have associated the lifting mechanism in mutually coacting pairs. By this construction, I have been enabled to substantially double the lift without adding to the minimum height of the platform from 45 the floor. This is extremely important be-

cause it is essential that these trucks be low and desirable that they have a large lift. I consider this feature both useful, and, broadly, new.

In the drawings:—Figure 1 is a side elevation of my truck partly in cross-section; Fig. 2 is a side elevation, partly in cross-section, of my truck; Fig. 3 is a plan view thereof; and Fig. 4 is a section on line 4—4 of Fig. 1.

The truck comprises an elevating platform A usually made and constructed of channel metal in skeleton form, as shown in Fig. 3. The truck frame proper comprises the bars B and B', each of broad U form. Bolted to the inturned portions B² and B'² at the rear end of the bars B and B' is an axle C having turned-down portions at its outer ends to accommodate the rear wheels a and a' of the truck. Secured to the front end of the bars B and B' are upwardly projecting supporting brackets D and D' carrying a support d for the swivel d' of the steering front wheel d². The swivel d' has a transverse bearing d³ upon its upper surface which carries a pin d⁵ which engages the bearings d⁴ upon the U-shaped member d⁶ through a bearing at the top portion of which, as at d⁷, is passed a spring-pressed handle d⁸ carrying a cross-rod d⁹ adapted to ride in slots d¹⁰ in the member d⁶, as above alluded to. Carried in the up-turned portions of the brackets D and D' are gudgeons e and e'. Upon these gudgeons are mounted the cams e² and e³, as shown in Figs. 1, 2 and 3. The cam e² has a slot e⁴ and a recess e⁵ therein, as shown in Fig. 1, and the cam e³ is in all respects similar thereto. Embracing each of these cams are fork-members f and f', slotted to embrace gudgeons e and e', as shown in Figs. 1 and 2, respectively, carrying cam rollers f² and f³ at their outer ends and prolonged, as at f⁴ and f⁵, at their inner ends for engagement with a shaft g forming a portion of the movable frame comprising members g, l, l', and m. The shaft g carries at each of its opposite ends cams. These cams are clearly shown in Fig. 4. Each cam comprises a cam portion proper and an adjacent geared portion similar in every respect except that it has teeth, while the other is smooth-faced to carry a load, the contour of the latter being coincident with the pitch line of the teeth of the other. g' and g² form one such cam. (See 110

Fig. 4). g^3 and g^4 form another revolvably mounted upon the same shaft but in opposite phase. g^5 and g^6 and g^7 and g^8 complete the cam equipment of the shaft g upon the opposite side of the track. Secured to the frame bars B are members h and h' having upon their upper surfaces rack portions h^3 and h^6 and smooth bearing portions h^4 and h^5 to coöperate with the cams g^3 , g^4 , and g^5 , respectively. Upon the under side of the platform A are also mounted bearing blocks k and k' having rack portions k^3 and k^8 and smooth bearing portions k^2 and k^7 to coöperate with the cam g^4 and g^2 , and the cam g^7 and g^8 , respectively.

Links l and l' connect shaft g with the shaft m at the rear of the truck, while secured to the shaft m are a set of cams corresponding in every detail with the cams just described, and upon the frame-bars B and B' and the platform A are bearing blocks having smooth and rack portions for coöperation with these cams in precisely the manner just described. Secured to the links l at two points thereof are forks n , n' , and o and o' . Rising from the frame bars B and B' are brackets p and p' and dependent from the bottom of the platform A are brackets p^3 and p^4 , these brackets being provided with pins, such as q , q^3 , q' , and q^2 . These pins are at all times embraced between the forks n and n' , o and o' and serve to hold platform A in prescribed relation to base B. Those at the rear function precisely as do those at the front. Upon the swivel platform of the portion D hereinbefore alluded to is mounted a pair of brackets s and s' carrying rollers s^2 and s^3 bearing against a plate s^4 mounted on the front of the platform A, as clearly shown in Fig. 2.

The operation of my truck is as follows: Referring to Fig. 1, when it is desired to raise the platform A, the handle d^8 is moved until its cross-rod d^9 takes into the slots e^4 of the cams e^2 and e^3 . These cams are then turned down about their gudgeons e and e' , their bearing surfaces e^2 drawing forks f and f' forward in an obvious manner. When the cams reach a substantially horizontal position, the rollers f^3 and f^2 on the forks f drop into the recess e^5 just as these recesses go past center relatively to the shaft g and the gudgeons e and e' . As the cam is dropped through this position or across centers, it is obvious that there is a toggle action and that the links f^4 and f^5 can not be retracted, and the platform, therefore, is locked in elevated position. When the platform is to be lowered, the cams are again swung back past center by means of the handle d^8 and cross-rod d^9 . As the links f^4 and f^5 are drawn forward as above described, the shaft g is drawn forward, and, through the intermediary of the links l and l' , the shaft m is also drawn

forward. The sets of cams hereinabove described, since each cam is provided with a toothed portion engaging a stationary rack upon the base portion or upon the platform, are rotated while the smooth portions of these cams moving in contact with the smooth bearing portions provided upon the platform A and the base portion B, respectively, force the platform A and the base portion B apart in an obvious manner. Thus it may be seen that the cams h^3 and h^4 , g^3 , g^4 , g^5 and g^6 of Fig. 1 operate to bodily raise the shaft g carrying platform A, while the cams g^7 , g^2 , g^7 and g^8 carried up with the shaft g tend to still further bodily raise platform A, while a simultaneous and exactly similar set of operations is going on at the rear of the truck. The forks n , n' and o and o' keep the platform from being separated farther than the limit prescribed by the lifting devices, while the rollers s^2 and s^3 keep the platform A from riding forward with the shafts g and m . It is to be particularly noted that while I have provided, substantially, a double-lift mechanism, yet, by placing my cams in pairs, I have not increased the minimum distance of the top platform from the floor. This is a very important feature of my invention, since these trucks for successful and practical operation should be as low as possible, but yet it is very desirable that they have a comparatively large lift.

Having now described my invention but recognizing that many departures and modifications may be made from the specific form in which I have chosen here to illustrate it, the scope of the invention being more truly defined and bounded in the following claims, I claim:—

1. In an elevating truck, a base member, a vertically movable lifting platform, a frame intermediate said platform and said member adapted to be longitudinally movable with respect to said member, cam devices on said frame in engagement with said base member and platform, and adapted to roll thereon when said frame is actuated, cams on said base, connecting means between said cams and said frame, a steering handle on said base and means independently movable therein to engage said last named cams whereby said platform may be elevated.

2. In a truck, in combination with a base and a lifting platform, a frame intermediate said base and platform, a shaft on said frame, cams on said shaft, engaging devices for said cams on the base, other cams on said shaft, engaging devices on said platform for the last-named cams, and means to shift the frame longitudinally with respect to the base and platform, whereby the platform may be separated from the base.

3. In a truck, in combination with a base and a lifting platform, a frame, a shaft on said frame, cams on the shaft, engaging devices for the cams on the base, engaging devices for the cams on the platform, said cams arranged for rolling contact with said devices, means to shift the frame longitudinally whereby the platform and the base may be separated, including means whereby the platform may be locked in its raised position.

4. In an elevating truck, including a base, a lifting platform, longitudinally-movable lifting cams intermediate said base and platform and arranged for rolling contact therewith, a steering handle, and means associated with the handle whereby the lifting cams may be moved to effect their lifting function, including means whereby the cams may be locked in their displaced position.

5. In an elevating truck, including a base, a lifting platform, cam engaging devices on said base and platform, longitudinally-movable lifting cams adapted for rolling contact with said devices, a steering handle, and means associated with the handle whereby the lifting cams may be moved to effect their lifting function, including means whereby the cams may be locked in their displaced position, and means for confining the platform at all times to precisely the distance from the base prescribed by the position of the lifting cams.

6. In a lifting truck, a swivel, a handle mounted on the swivel, a frame, a pair of

cams mounted thereon and provided with slots and recesses, a bar in the handle operable at the will of the operator to engage in said slots to actuate said cams, lifting devices, and links connecting said devices, said links being operable with the cams and adapted to co-operate with the cam faces and recesses, the whole being so arranged that the cams and links form toggles.

7. In a mechanism of the class described including a base, and a movable platform, a frame intermediate the base and the platform, lifting devices on the frame having rolling engagement with said base and platform and means whereby the rate of vertical movement of the platform varies with the longitudinal displacement of the frame.

8. In an apparatus of the class described, including a base and a platform movable away from the base, means for moving the platform away from the base, said means including a frame, cam devices mounted on the frame and engaged in rolling contact, respectively, with the base and the platform, said cam devices being so arranged that the lifting rate of the platform varies with the displacement of the cams from their starting position, and devices operable at the will of the operator to move said frame.
